Patented June 15, 1915.

UNITED STATES PATENT OFFICE.

MATHIAS F. BOHR, OF STICKNEY, SOUTH DAKOTA.

LOCKING DEVICE.

1,143,029.

Specification of Letters Patent. Patented June 15, 1915.

Application filed March 18, 1914. Serial No. 825,667.

To all whom it may concern:

Be it known that I, MATHIAS F. BOHR, a citizen of the United States, residing at Stickney, in the county of Aurora, State of South Dakota, have invented certain new and useful Improvements in Locking Devices; and I do hereby declare the following to be a full, clear, and exact description of the invention, such as will enable others skilled in the art to which it appertains to make and use the same.

This invention relates to certain novel and useful improvements in locking devices, and while I have in the present instance shown and described my invention as employed in connection with what is commonly known as a buckling end gate, I wish it to be understood that the invention is not limited in its useful application to this particular purpose, as it is equally well adapted for use in connection with barn doors, the side walls of wagon bodies, boxes and similar structures.

In carrying out my invention it is my purpose to provide a locking device by means of which the gate, door or other structure may be firmly and securely fastened so that the liability of its being accidentally opened is obviated.

Furthermore, it is my purpose to provide a locking device of this character which will embody in its construction the desired features of simplicity, efficiency and reliability, and which may be manufactured and marketed at a relatively low cost.

In the accompanying drawings: Figure 1 is a view of a portion of a wagon box having an end board applied thereto, and showing my lock as employed in connection therewith. Fig. 2 is a plan view of the part shown in Fig. 1. Fig. 3 is a cross sectional view taken on the line 3—3 of Fig. 2, the portion of the lock board 5 being omitted for the sake of clearness. Fig. 4 is a similar view but showing the lock in its withdrawn or unlocked position. Fig. 5 is a view of a modified form of lock adapted to be employed in connection with a barn door or the like, certain of the parts of the lock being omitted. Fig. 6 is a plan view of the keeper bar which is attached to the inside wall of the end gate. Fig. 7 is a detail view of a portion of the locking spindle.

Referring now to the accompanying drawings in detail, the letter A designates, in the present instance, the rear portion of the wagon box provided with the ordinary vertical retaining cleats 1. The end gate is indicated as an entirety by the letter G and includes the relatively long section 2 and the relatively short section 3, the two sections being connected by means of the hinges 4, so that the gate may buckle outward. The shorter end gate section has rigidly connected thereto a lock board 5 which is tapered or reduced at one end as at 6, this tapered end having an open-mouthed slot 7 for the purpose hereinafter described.

The locking device proper is mounted upon the relatively long section 2 of the tail board and embraces a sleeve 8 seated in the bore 9 extending through the board, this sleeve 8 having a flange 10 at one end bearing against one side of the board and a collar 11 which bears against the opposite side 7 of the board.

The numeral 12 indicates a post having a reduced threaded shank 13 which is screwed into the threaded bore 14 of the sleeve 8, a shoulder 15 being formed between the outer end of the threaded shank of the post and the body of such post, this shoulder bearing against the flange 10 which is at the outer face of the tail gate section 2. This post 12 which is adapted to be rotated or turned is provided with a horizontal bore 16 extending therethrough from end to end, the outer end of the bore terminating in an enlargement or recess 17 which is formed in the elongated or rectangular head 18 of the post, this elongated head forming the locking bar of the device, as will be hereinafter understood.

Extending through the bore 16 of the post 12 is a spindle 19, the outer end of which terminates in a transverse bar-like head 20 having the handle 21 cast therewith. Carried by the spindle below the head are the flanges 22—22 which seat in the recess 17 formed in the head 18 of the post 12. As will be noted, the spindle 19 extends entirely through the bore 16 of the post 12, and consequently its inner end projects beyond the inner face of the tail board section 2 and also extends through the bore 23 of the spring 24 which is in the form of a

bowed metallic strap which bears against the inner face of the board section 2. A wearing plate 25 is carried by this spring strap 24 and is also formed with a central 5 bore alining with the bore in the strap. The terminal of the shank 19 carries a rectangular locking block 26. The numeral 27 indicates a vertical bar or block which is fastened over the strap spring and over 10 parts of the lock which lie at the inner face of the board section 2, this block being grooved and cut to constitute a casing for these parts. As will be seen, such a block comprises a body portion 28 formed on its 15 inner face with the longitudinal grooves 29 which are tapered or deepened toward the center to accommodate the adjacent portions of the strap spring 24. The inner ends of these two grooves 29 merge in the enlarged 20 recess 30 deepened or cut out at its center as at 31 to form a smaller supplemental recess.

The numeral 32 designates a rectangular metallic plate of a size sufficient to fit snugly 25 within the recess 30 and form a floor therefor, this plate 32 having a rectangular central opening 33 of the same size as the recess 31 and registering therewith. It will be noted that the slot or opening 33 in the plate 30 is of sufficient size to accommodate the rectangular locking plate 26 and permit the latter to lie or seat within the recess 31 at desired times. If desired, a coil spring 34 may be interposed between the head 20 of the 35 spindle 19 and the bottom of the recess 17 of the post 12 to tension and cushion these parts.

The above is a description of the mechanical features of my invention, and the operation 40 is as follows: When it is desired to close and lock the gate, the sections 2 and 3 are arranged in a straight line with each other and held by the cleats 1, and the locking board 5 will lie over against the outer 45 face of the sections as shown in Fig. 1. The handle 21 is turned so that the locking block 26 at the end of the spindle 19 will be turned to such position that it will register with and be forced into the recess 31 by the outward 50 pressure of the bowed spring 24, and under these conditions the locking head or bar 18 of the post 12 will turn with the latter and lie crosswise of the open-ended slot in the end of the locking board, and bearing 55 against such board will clamp the latter against movement, thus locking the parts together. If it is desired to unlock the board, the handle 21 is pulled outward against the action of the bowed spring 24, 60 thereby depressing the spring or flattening it and withdrawing the locking block 26 from the recess 31. When it has been withdrawn from the recess, the operator gives the handle a quarter of a turn, which is per-

mitted because the locking block has been 65 withdrawn from the recess 31 and this causes the locking block to assume a position spanning or extending transversely of the opening 32 of the plate 33. At the same time this turning movement of the handle 70 will turn the locking head or bar 18 from a position transverse of the open ended slot to a position longitudinal thereof and thus permit the tail locking board to be withdrawn, and the tail board opened or removed. 75

It is to be understood that the flanges 22 of the bar-like head 20 are made of sufficient depth so that when the locking block 26 is withdrawn from its socket by pulling forward or outward on the handle 21, the inner 80 portion of these flanges 22 will still engage in the recess in the head bar 18 so that when the handle is turned, although the block 26 is out of its socket, these flanges will still engage with the walls of the slot in the head 85 bar 18 and thus turn the head bar and its connected parts.

It will be noted that I have provided an exceedingly simple, yet efficient form of locking device which may be used for a 90 number of purposes, such for instance, in connection with wagon end gates, as herein described, or with wagon bodies, or boxes, trunks, doors, or indeed, under any conditions where its use might be deemed ad- 95 visable.

In case it should be desired to use the device on a door, such as a barn door, an additional handle 35 may be provided at the end 100 of the shank 19, which in this instance is 105 projected beyond the locking block 26. This handle will lie at the inside of the door so that the latter may be locked and unlocked from the inside, and under such conditions it will, of course, be evident that instead of 110 pulling on the handle line to release the locking block, the handle will be pushed to force such locking block from its locking recess.

While I have herein shown and described 110 one particular embodiment of my invention, I wish it to be understood that I do not confine myself to all the precise details of construction herein set forth by way of illustration, as modification and variation may 115 be made without departing from the spirit of the invention or exceeding the scope of the appended claim.

What I claim is:

The combination with a wall and a member to be locked thereto, of a locking device carried by the wall comprising a rotatable post having a locking head adapted to fasten the member to be locked, a spindle extending through said post, said spindle having means 120 for engaging with the head of the post to rotate the latter, a locking block carried at the inner end of the spindle, a keeper for the 125

locking block, means normally forcing the locking block of the spindle into locking engagement with the keeper, and means for withdrawing the locking block from the keeper and turning said locking block to release the locked member from the wall.

In testimony whereof, I affix my signature, in the presence of two witnesses.

MATHIAS F. BOHR.
